(57) **CLAIM**

The ornamental design for the leverage nail puller, as shown and described.

DESCRIPTION

FIG. 1 is a right side view of the leveraged nail puller of this invention;

FIG. 2 is a left side view;

FIG. 3 is a top view;

FIG. 4 is a bottom view;

FIG. 5 is a back view; and,

FIG. 6 is a front view of the invention.
